UNITED STATES PATENT OFFICE.

WILLIAM HAILES, OF ALBANY, NEW YORK, ASSIGNOR OF ONE-HALF TO
HARRIET K. DAVY, OF HYDEVILLE, VERMONT.

REVERSIBLE AND VENTILATING POT-HOLE RING FOR STOVES.

SPECIFICATION forming part of Letters Patent No. 269,206, dated December 19, 1882.

Application filed October 2, 1882. (No model.)

To all whom it may concern:

Be it known that I, WILLIAM HAILES, a citizen of the United States, and a resident of the city of Albany, in the county of Albany and State of New York, have invented a new and Improved Reversible and Ventilating Pot-Hole Ring for Stoves, of which the following is a full, clear, and exact description, reference being had to the accompanying drawings, forming a part of this specification.

My invention relates to a new and improved pot-hole ring which is reversible for operations in a stove, and in one position adapted to be used as a reducing-ring, the same as pot-hole rings heretofore made. While in a reversed position it will, in a stove burning hard coal, with a pot-hole cover over the same, operate to effect a dampening of the fire by its admitting air over the same, and with a cooking-vessel placed on it the ring will operate to cause boiling or cooking to proceed slowly and without scorching the food; and when used in a stove burning soft coal or wood the said ring, with a cover placed over the same, will admit air into the combustion-chamber to be mingled with the heated gases from the coal, and thereby contribute to their combustion before their escape to the exit-flue; and when employed with a hood inclosing a cooking-vessel supported on said ring the ring will operate to admit the passage of the steam and odors arising from the vessel into the combustion-chamber or flue leading from the same to the exit.

My invention in one part consists of a pot-hole ring formed by an external ring-flange and a vertically-projecting flange provided with a series of horizontal notches or ports made in its projected horizontal surface, the ring being adapted to be supported from either of its sides from the internal ring-flange made with the pot-hole of a stove-top plate. In another part it consists in the combination, with a stove-top provided with a pot-hole, of this new pot-hole ring and a cover to the same; and in another part of my invention it consists in the combination and arrangement, with a stove-top provided with a pot-hole, and a hood adapted to be supported by the stove-top and enveloping a cooking-vessel, of the improved pot-hole ring hereinafter described.

The object of my invention is to provide a pot-hole ring which will be adapted to operate as a reducing-ring when in one position in a stove-top, and in a reversed position, with a cover over it, operate to admit the passage of air into the combustion-chamber to dampen down the fire when hard coal is used as fuel, and contribute to the combustion of the gases escaping from the burning wood or soft coal when used as a fuel, and operate to admit the passage of the steam and odors escaping from a hooded cooking-vessel into the combustion-chamber or a flue leading from the same. I attain these objects by means illustrated in the accompanying drawings, in which—

Figure 1 represents a sectional elevation of a stove-top, my improved pot-hole ring, and a cooking-vessel, the ring in position as a reducing-ring. Fig. 2 is a sectional elevation of the same with the ring in reversed position and the vessel enveloped by a hood. Fig. 3 is a perspective view of a section of my improved ring and a section of a stove-top, illustrating the peculiar feature of the ring and its position when operating differently from a reducing-ring. Fig. 4 is a plan view of the ring when serving the purpose of a reducing-ring. Fig. 5 is a plan view of the ring when in position for admitting air or steam and odor to the fire; and Fig. 6 is a sectional elevation of the ring when covered by a pot-hole cover and in position in the stove-top for the passage of air to the fire for dampening the same when hard coal is used as fuel, and for burning the hot gases escaping from the top surface of the fire when soft coal or wood is used as fuel.

The same letters of reference indicate like parts throughout the several views.

In the drawings, A represents the top plate of the stove, and a is the combustion-chamber. B is a pot-hole made in top plate, A, and provided with the usual flange-seat, b, all of which parts are well known.

C is my improved and new pot-hole ring, which ring is made with form and outer diameter corresponding with that of pot-hole B it is to be used with. The said ring is composed of an outer or external flange, c, corresponding with the sunken flange-seat b of the pot-hole, and the internal vertically-projecting

flange, c' . In the projecting horizontal surface of flange c' is made a series of notches, e , placed at intervals apart, so as to produce a crenelled projecting flange. When said flange is covered over by a pot-hole cover or the bottom of a vessel the said notches operate as ports for the passage of air or steam and odors to the fire below the stove-top.

In the drawings are shown an internal series of vertical notches, e' , extending from notches e downward through the entire vertical extension of flange c' , as shown. These notches e' operate as vertical ports when the pit of a cooking-vessel sets within the opening of the ring, as shown in Fig. 2. When the ring is made to be used with vessels having plain flat bottoms these vertical slots may be dispensed with. Holes pierced in and through flange c' will serve the same purpose, though more expensive to produce than the notches.

When my improved pot-ring is placed in position in the pot-hole, with its crenelled or port side downward, as shown in Figs. 1 and 4, the ring will operate as a reducing-ring, the same as an ordinary pot-hole ring, and will operate as a seat for supporting a cooking-vessel of smaller diameter than that required to fill the pot-hole B proper of the stove. When the ring is placed in a reversed position in the pot-hole, with its crenelled side uppermost, as shown in Figs. 2, 3, 5, and 6, the operations of the ring will be different and will be varied accordingly as it is used, when hard or soft coal or wood is employed as fuel, with a cover or a cooking-vessel only, or a vessel and hood inclosing the same. When the ring is being used with a stove burning soft coal, and is placed in the pot-hole in position shown in Figs. 2, 3, 5, and 6, and covered by a cover, D , as in Fig. 6, or with a vessel without a hood, the notches or ports e will operate as passage-ways for the passage of small streams or currents of air from over the stove-top into the combustion-chamber to be mingled with the gases escaping from the top surface of the fuel, and thereby contribute to their more perfect combustion before escape to the exit.

When hard coal is employed as fuel and a cover is placed over the ring, as in Fig. 6, air will have passage from over the top of the stove into the combustion-chamber, and a dampening of the fire will be effected, and the rapid combustion of the fuel will be prevented, and all necessity of tipping the covers for ventilating the apartment or cooling the top plate of the stove will be obviated. With hard coal as fuel in the stove, when a cooking-vessel is placed on the ring in position in Fig. 2, without a hood, the passage of air from without into the combustion-chamber will so affect the combustion that cooking or boiling will proceed slowly and without scorching or burning the articles of food being cooked. With hard or soft coal or wood as fuel in the stove, when the pot-hole ring is placed in position in the pot-hole so that the crenelled or port side or flange

is uppermost, and a vessel inclosed by hood H is supported on said ring, as illustrated in Fig. 2, the steam and odor escaping from the vessel will enter the chamber formed between the vessel and hood and pass thence through the several ports into the combustion-chamber, as they will be drawn by the draft of the chimney and made to mingle with the gases in their passage toward the exit.

In Figs. 2, 5, and 6 arrows indicate the direction of the passage of the air and the steam and odor through the ports to the combustion-chamber under the several conditions above mentioned, by which the several operations are effected by the use of my new and improved ring in stoves burning hard and soft coals, and with covers and with hooded cooking-vessels, respectively, as above described, whereby an operator will have a more perfect control over the combustion of the fuel to increase or lessen the same, and also better regulate the progress of the cooking being done.

By employing my crenelled or air-induction ring in a stove with a cover placed over the same, and a vessel placed on said cover and inclosed by hood H , (the cover arranged as illustrated in Fig. 6,) the process of cooking may be made to be more slow than when the cover is not employed, and the vessel is supported directly from the top surface of the ring, as the cooking will be done substantially in a vacuum, with a plate intervening between the bottom of the vessel and the fire.

Having described my invention, what I claim, and desire to secure by Letters Patent, is—

1. A pot-hole ring having an external flange and an offsetting internal flange provided with notches or ports, the former extending horizontally from the latter, and the latter projecting vertically from one side of the former, and the whole as a pot-hole ring adapted to be used in reversed positions with a pot-hole of a stove, as a reducing-ring, or as an air-induction ring, in the manner and for the purposes set forth.

2. A pot-hole ring having flanges c and c' , the flange c' being provided with notches or ports e , either with or without ports e' , and adapted for use substantially as described, for the purposes set forth.

3. The combination, with a stove-top provided with a pot-hole, of a pot-hole ring adapted to have support from the sunken annular flange-seat of the pot-hole, and provided with a vertically offsetting crenelled flange, which will admit the passage of air or steam, or both, beneath a vessel or cover supported on said ring, substantially as set forth.

4. The combination, with a stove-top provided with a pot-hole, of the crenelled ring C and cover D , substantially as and for the purposes set forth.

5. The combination, with a stove-top provided with a pot-hole, and a hood inclosing a vessel supported over said pot-hole, of the

crenelled ring C, arranged between said pot-hole and vessel, with its notched or port side upward, and communicating between the chamber-room between said hood and vessel and the combustion-chamber beneath said stove-top, for operations substantially as set forth.

6. The combination, with a stove-top provided with a pot-hole, of crenelled ring C, cover D, and hood H, inclosing a cooking-ve-

sel supported on said cover, said cover being supported on the notched or port side of said ring, substantially as and for the purpose set forth.

WILLIAM HAILES.
